UNITED STATES PATENT OFFICE.

MAX N. ALMQQUEST AND ANTHONY B. JABLONSKI, OF MILWAUKEE, WISCONSIN.

YARN BALLOONER.

Application filed June 6, 1927. Serial No. 196,855.

This invention relates to yarn ballooners. In unwinding yarn from cones, such for example, as silk, cotton, or other yarn, it is the usual practice to carry the cone within 5 a pan or other support and to unwind it by pulling directly upwardly upon the thread or yarn. This causes the thread to bind against the body of the cone and when it encounters any knots it usually breaks the 10 yarn. When silk is used, extreme difficulty is experienced in splicing the yarn or else the entire batch has to be discarded.

This invention is designed to overcome the defects noted above and objects of such 15 invention are to provide an unwinding device which causes the yarn to balloon, that is to say, to project itself substantially radially outwardly from the cone, although one portion of the yarn may be pulled directly 20 upwardly. The device provides means interposed between the straight, upwardly extending stretch of yarn and the cone so as to cause the intermediate portion of the 25 yarn between the cone and the device to bow outwardly in a big loop and to thus draw directly outwardly from the cone and not upwardly therefrom, thus avoiding any 30 possibility of the yarn's becoming entangled in knots or projections from the cone.

Further objects are to provide a device 35 which although possessing the characteristics noted above does not have any moving parts, but in which the parts are stationary and the yarn itself travels about the parts, thus avoiding any wear whatsoever.

Further objects are to provide a device 40 for unwinding yarn from a cone in which the parts are adjustable to accommodate yarns of different sizes, and in which the device is securely supported so as to maintain it in proper relation to the axis of the cone.

Further objects are to provide a device 45 having the characteristics enumerated above which nevertheless is of extremely simple construction, which is easily produced, and which does not require a great accuracy of adjustment.

An embodiment of the invention is shown 50 in the accompanying drawings in which:

Figure 1 is a sectional view through the

device showing a cone in position and showing in full lines one position of the yarn and in dotted lines several other positions;

Figure 2 is a plan view of the structure 55 shown in Figure 1;

Figure 3 is an enlarged sectional view through the upper portion of the device.

Referring to the drawings, it will be seen that the device comprises the usual pan 60 1 provided with an upstanding central portion 2 upon which the cone is slipped. The cone is regularly formed upon a conical core 3 usually of cardboard, and is usually wound so as to provide a cone of yarn, as 65 indicated by the reference character 4.

In practicing this invention, the pan is provided with any suitable means for supporting the vertical upright 5. For example, it may be provided with an apertured 70 lug 6 which is threaded for the reception of the lower threaded end of the upright 5. This upright carries a slid able member 7 which may be locked thereto by means of the set screw 8, which latter may be 75 formed in the manner of a thumb nut or wing nut. The member 7 is provided with an outwardly projecting arm 9 which is rigidly secured thereto in any suitable manner as for example by means of a threaded 80 portion screwed into the member 7 and locked thereto by the lock nut 10, as shown in Figure 1. The member 9 extends outwardly and downwardly and carries a ring 11 at its outer end in axial alignment with 85 the cone. This ring is provided with a bottom disc 12 which may be integral with a flange or sleeve 13 secured within the ring 11. Preferably, the sleeve is provided with a porcelain wear resisting bushing 14, as 90 shown most clearly in Figure 3.

It is to be noted that the disc 12 is provided with a rounded and upstanding annular flange 15.

A capping sleeve 16 is mounted upon the 95 top of the conical core 3 of the cone and is preferably provided with a centrally located spike 17 which may be projected through the upper portion of the core 3, as shown in Figure 3. It is provided with a 100 downwardly extending flange 18 which is slipped outside of the upper end of the

core 3 and is preferably provided with bevelled lower edges 19. The sleeve or member 16 is provided with an upwardly extending annular flange 20 which is arranged 5 in spaced relation to the upturned flange 15 of the disc 12, it being noted that such upturned flange 15 is slightly smaller in diameter than the internal diameter of the flange 20.

10 In using the device, the yarn is led from the cone upwardly over the flange 20 beneath the flange 15 and threaded through the sleeve 14. It then passes upwardly to the winding mechanism.

15 When the device is in use, the yarn balloons out into the form indicated at 21 in Figure 1, and as the cone continues to unwind it assumes various positions, as shown in dotted lines in Figure 1.

20 It is to be noted that there is not a direct upward pull of the yarn from the cone as in the usual unwinding operation, but instead, means are provided for causing the yarn to balloon outwardly so that it pulls in a radial 25 plane from the cone. The upper portion of this revolving loop is deflected downwardly between the flange 15 and the flange 20, as shown in Figure 3, so as to complete or maintain the looped or ballooned formation 30 of the revolving loop.

It will be seen, therefore, that the tendency of the yarn to break from becoming entangled with knots or projections from the cone is greatly reduced by this invention as 35 the yarn draws away from the cone in a radial plane and does not draw directly upwardly therefrom.

From actual tests conducted with a device constructed in accordance with this disclosure, it has been found that the yarn freely unwinds and does not catch upon knots or projecting portions, but bows outwardly and maintains a revolving loop so as to avoid any possibility of entanglement.

45 Although the invention has been described in considerable detail such description is intended as illustrative rather than limiting as the invention may be variously embodied and as the scope of such invention is to be determined as claimed.

We claim:

1. An unwinding device for yarn comprising means for receiving the yarn, a pair of members positioned above the yarn receiving means and of annular contour and adapted to have the yarn threaded between such members, one of said members having a centrally located discharge aperture through which the yarn is drawn, said members being adapted to depress the yarn above the yarn receiving member, whereby a looped formation of the passing yarn is maintained.

60 2. An unwinding device for a cone of yarn comprising a support for positioning the

cone of yarn with its axis upright, a member adapted to engage the upper end of the cone and having an annular flange, and a second member positioned above said first mentioned member and having an annular flange arranged in spaced relation to said first mentioned annular flange and having a central aperture, said members being adapted to have the yarn threaded between the annular flanges and passed through the central aperture of said last mentioned member, whereby the yarn may be drawn directly upwardly from said last mentioned member and will balloon outwardly between the cone of yarn and the annular flanges.

3. An unwinding device for a cone of yarn comprising a support for positioning the cone of yarn with its axis upright, a member adapted to engage the upper end of the cone and having an annular flange, and a second member positioned above said first mentioned member and having an annular flange arranged in spaced relation to said first mentioned annular flange and having a central aperture, said members being adapted to have the yarn threaded between the annular flanges and passed through the central aperture of said last mentioned member, said second mentioned annular flange being positioned slightly within said first mentioned annular flange to cause the yarn to be deflected angularly downwardly as it passes towards the central aperture.

4. An unwinding device for a cone of yarn comprising a base member provided with an upright central portion adapted to receive the core upon which the cone of yarn is wound, a member removably attached to the upper end of said core and having an annular upstanding flange at its upper end, a support extending upwardly from said base member, a laterally projecting arm carried by said support, and a second member carried by said arm and positioned over said first mentioned member, said second member having an annular flange spaced inwardly with reference to said first mentioned annular flange and having a central aperture, whereby the arm may be threaded between said flanges and may pass outwardly through said central aperture.

5. An unwinding device for a cone of yarn comprising a base member provided with an upright central portion adapted to receive the core upon which the cone of yarn is wound, a member removably attached to the upper end of said core and having an annular upstanding flange at its upper end, a support extending upwardly from said base member, a laterally projecting arm carried by said support, and a second member carried by said arm and positioned over said first mentioned member, said second member having an annular flange spaced inwardly

with reference to said first mentioned annular flange and having a central aperture, whereby the arm may be threaded between said flanges and may pass outwardly through said central aperture, said laterally projecting arm being adjustably mounted upon said support.

In testimony that we claim the foregoing we have hereunto set our hands at Milwaukee, in the county of Milwaukee and State of Wisconsin.

MAX N. ALMQUEST.
ANTHONY B. JABLONSKI.
